UNITED STATES PATENT OFFICE.

ERNEST H. BENNETT, OF EAST ORANGE, NEW JERSEY, ASSIGNOR TO JOHN H. BROMLEY AND EDWARD BROMLEY, COPARTNERS, TRADING AS JOHN BROMLEY & SONS, OF PHILADELPHIA, PENNSYLVANIA.

DESIGN FOR A RUG.

SPECIFICATION forming part of Design No. 36,774, dated February 2, 1904.

Application filed December 28, 1903. Serial No. 186,929. Term of patent 3½ years.

To all whom it may concern:

Be it known that I, ERNEST H. BENNETT, a citizen of the United States, residing at East Orange, in the State of New Jersey, have invented a certain new, original, and ornamental Design for a Rug, of which the following is a specification, reference being had to the accompanying drawing, forming a part thereof.

In said drawing is shown a plan view of one half of the design, the other half (not shown) to being a duplicate thereof.

I claim—

The ornamental design for a rug, as shown.

ERNEST H. BENNETT.
